PAUL RISSMANN, OF DETROIT, MICHIGAN, ASSIGNOR TO FISHER BODY CORPORATION, OF DETROIT, MICHIGAN, A CORPORATION OF NEW YORK.

PULL-STRAP FIXTURE.

1,426,106.

Specification of Letters Patent. Patented Aug. 15, 1922.

Application filed May 18, 1921. Serial No. 470,648.

To all whom it may concern:

Be it known that I, PAUL RISSMANN, a citizen of the United States, residing at Detroit, in the county of Wayne and State of Michigan, have invented certain new and useful Improvements in Pull-Strap Fixtures, of which the following is a specification.

This invention relates to attaching fixtures for securing a pull strap to a window sash. In automobile closed body construction the so-called pull strap is still used on some windows. This strap is now usually made up of a center of burlap strips and has a backing of waterproof fabric and a face that is usually trimmed in the same goods with which the car is trimmed. It is customary ordinarily to attach these straps to the metal channel bar that forms the lower support of the sash by means of a loop. A metal loop is usually provided on the side of the channel bar and the pull strap is looped through this and then stitched to form a loop. The trouble with this construction is that it frequently tears out because the stitching or material is not strong enough to stand the very severe tension that is often put on the strap, especially if the window sticks.

It is the object of the present invention to provide an attachment which comprises a strap fixture which may be quickly attached to the ends of the strap and which may be detachably engaged with a special fixture secured on the bottom of the sash bar.

In the drawings,—

Fig. 1 shows the usual interior construction of a closed body indicating the pull strap.

Fig. 2 shows how the pull strap is fastened to the bottom of the sash. This is simply a fragmentary view of the bottom of the window.

Fig. 3 is a section on the line 3—3 of Fig. 2.

Fig. 4 is a detail in perspective of the strap fixture parts disassembled.

Fig. 5 is a perspective view of the fixture for attachment to the bottom of the sash.

a designates the ordinary pull strap which is adapted to raise and lower the window *b*. These windows are now made with no sash bar at the top and frequently none at the side. However, they have a channel bar *c*

at the bottom in which the lower edge of the glass rests. At the bottom of this channel bar is spot-welded or riveted a sash fixture *d* which comprises simply a strip of metal stamped out as shown in Fig. 5, forming a loop *e* having a pair of ears *f*, *f* extending forward.

The strap fixture comprises an angle plate or stamping *g*. One web *r* of this angle plate is provided with extending ends *h*. The other web *s* is provided with struck-in prongs *j*. The clamping plate *k* is adapted to match the web *s* of the angle plate and is provided with a plurality of struck-in projections *l* at the end of which are slots *m*. A machine can be provided with suitable dies to hold the angle plate *g* and the clamping plate *k*. The end of the strap can be interposed between the two plates and the prongs *j* can be driven through the strap end and through the slots *m* of the plate *k*. The prongs are then turned over by the press into the depressions *l* which are just the shape to nicely receive them. This avoids their projecting to any extent above the surface of the plate *k* and makes a neat, clean job of it.

When this has been done the fixture is neatly attached to the pull strap with the end extensions *h* extending to the sides of the strap. The strap may then be inverted, as shown in Fig. 2, the back of the strap facing the observer. The web *r* with the end extensions *h* is then slipped into the loop *e*. The ears *f* are then simply bent up beyond the end extensions *h*, locking the fixture into the sash fixture.

These two fixtures not only form a strong attachment for the pull strap to the window sash but the strap fixture forms a very neat salvage for the end of the strap. The strap fixture may be applied by a suitable set of dies and a small press very rapidly so that the article is a large production proposition.

What I claim is:

1. An attachment for securing pull straps to window sashes, having in combination, a loop provided with ears and adapted for attachment to the bottom of a window sash, and a pull strap fixture in the form of an angle plate and clamp having end extensions on one of the webs, said web adapted to engage between the loop and the bottom of the window sash and be removably se-

cured therein by turning the said ears of the loop up to a right angular position to engage the said end extensions.

2. An attachment for securing pull straps 5 to window sashes, having in combination, a fixture for attachment to the bottom of a window sash, and a pull strap fixture comprising an angle plate provided with one web arranged to be clamped into the sash 10 fixture and the other web having prongs and a clamping plate provided with slots adapted to receive the prongs that are impaled through the end portions of the pull strap and are then turned over on the clamping 15 plate to secure the two plates together and to opposite sides of the pull strap.

3. An attachment for securing pull straps to window sashes, having in combination, a fixture for attachment to the bottom of the 20 window sash and a pull strap fixture, comprising an angle plate provided with one web clamped onto the sash fixture and the other web arranged for engagement on one side of the end of the pull strap, a clamping 25 plate arranged to engage on the opposite

side of the end of the pull strap, and means piercing the end of the pull strap for clamping the two plates together and anchoring the same on the end of the pull strap.

4. An attachment for securing pull straps 30 to window sashes, having in combination, a fixture in the form of a stamping provided with a loop portion and having forwardly-facing ears at the ends of the loop portion, and a pull strap fixture comprising an angle 35 plate provided with a web having end extensions adapted to be locked in behind the ears of the window fixture loop when the ears are turned up right-angularly, the other web of the angle plate being provided 40 with struck-out prongs, and a clamping plate having slots adapted to register with said prongs when the prongs are impaled through the end portion of the pull strap, the said prongs being then passed through 45 the said openings in the clamping plate and turned over to complete the pull strap fixture.

In testimony whereof I affix my signature.
PAUL RISSMANN.
